UNITED STATES PATENT OFFICE.

ERNEST RICHARDSON, OF BEAVER FALLS, PENNSYLVANIA.

OVEN, REFRIGERATOR, AND SIMILAR RECEPTACLE.

1,013,313.

Specification of Letters Patent.

Patented Jan. 2, 1912.

Application filed July 20, 1911, Serial No. 639,637.

To all whom it may concern:

Be it known that I, ERNEST RICHARDSON, a citizen of the United States, residing at Beaver Falls, in the county of Beaver and State of Pennsylvania, have invented new and useful Improvements in Ovens, Refrigerators, and Similar Receptacles, of which the following is a specification.

My invention relates to improvements in shelves and shelf-supports for ovens, refrigerators or other receptacles, and its object is to provide removable shelf supports and shelves made preferably of wire, so constructed that the shelves may be wholly or partially withdrawn from their supports. I prefer to make the parts of wire because of its lightness and cheapness, and also because wire permits the construction of open work which can be readily cleaned.

Referring to the accompanying drawings, Figure 1 is a horizontal section through an oven showing the preferred form of my invention. Fig. 2 is an elevation of the lining of a side of the oven with a shelf support thereon, the top, bottom, and back linings being in vertical section. Fig. 3 is a perspective view of a shelf-support showing a fragment of a shelf in its partially withdrawn position. Fig. 4 is a perspective view of a shelf adapted to the shelf supports.

On the drawing, 1, 2, 3, and 4 designate corner posts, to the outer faces of which the outer plates or sides 5, 6, and 7 of the oven are attached. 8, 9, and 10 designate the linings standing opposite the respective sides 5, 6, and 7 and attached to the inner faces of the said posts. 11 is the bottom plate and 12 the top lining for the oven; and 13 is the door hinged to the post 1 and adapted to close the front of the oven. No novelty is claimed for the structure so far described.

For the present invention the inclosing walls of the oven, refrigerator, or analogous article may be constructed as desired, provided it will permit the shelf-supports and shelves hereinafter described to operate in the manner intended.

To each of the side walls or linings 8 and 10, I secure a shelf support constructed preferably as follows: A substantially rectangular frame of wire is formed having the vertical members 14 and 15 and the upper and lower horizontal members 16 and 17, the latter member 17 resting on the bot-

tom 11 and provided with horizontal feet 18 also resting on the bottom 11 and projecting toward the interior of the oven to support the frame more firmly and keep it from any tendency to warp toward the interior of the oven. The frame described normally rests flat against the adjacent lining and has the forwardly projecting wire hooks or hinge members 19 which rest and swing in the eyes or mating hinge members 20 secured to the linings 8 and 10. The members 14 and 15 are connected together by any desired number of horizontal shelf supporting wires 21 which have their end portions bent toward the walls of the oven so that the intermediate portions project into the oven slightly to form rails or rests for the slidable shelves presently to be described.

Each shelf is preferably a rectangular frame of wire having the sides 22, 23, 24, and 25, the sides 23 and 25 being joined by the parallel horizontal wires 26. When the shelf is wholly in the oven, the sides 22 and 24 lie close to and parallel with the oven sides 7 and 5, and a portion of the sides 23 and 25 lie upon the wires 21. The side 25 is provided on its under side near each end with a stop in the form of a piece of wire 26' which extends downwardly about the diameter of the wires 21 and then outwardly parallel with the wire 25 so as to extend under the adjacent wire 21 and approximately to the adjacent side 22 or 24. The sides 16 and 17 of the swinging shelf-supporting frame have connected thereto a vertical wire which has the outwardly-extending loops or bends 27 connected to each shelf-supporting wire 21 at the place marked 28 which is close to the point where its front end is bent toward the adjacent side of the oven. I have connected the wires 21 to the upper part of the outer end loops 27 in order that the stop wires 26' will, when the shelves are drawn outwardly, engage the loops, which constitute stops for the wires 26'.

A shelf when drawn forwardly as shown in Figs. 1 and 3 obtains leverage on both sides of its supporting wires 21, and can sustain such articles as are usually placed in ovens or the food compartments or refrigerators, or the like. When the shelves are pushed entirely into the oven, the stops 26' lie back of the inwardly projecting portions of the supporting wires 21 (Fig. 2), so

that the rear ends of the shelves may be lifted and the shelves then drawn forwardly with the stops 26' above the wires 21 until the shelves are entirely out of the oven.

5 When the shelves have been removed from the oven, the shelf-supporting frames may be swung on their hinges so as to stand outside of the oven, as shown in dotted lines in the case of one frame at the left-hand side 10 of Fig. 1, where they may be cleaned and where they do not interfere with the cleaning of the interior walls of the oven.

If preferred, the frames may be hung on the hooks 29, the sides 16 being provided 15 with the bends 30 to receive the hooks in order to prevent any sliding of the frames. I do not limit my invention to the simultaneous employment of the hinges and the hooks in the same oven or other structure.

20 I claim—

1. In an oven, refrigerator, or the like, a receptacle, a pair of opposing vertical wire frames, each frame having opposing horizontal shelf-supporting wires connected thereto and projecting into the receptacle, 25 a shelf slideable on the opposing wires and having at its rear portion an outwardly projecting finger adapted to extend below the adjacent shelf-supporting wire, a vertical support for the forward end of the shelf-supporting wires having a stop in the path of the shelf when drawn outwardly with the finger beneath the said wire, and means 30 for securing the frames to the interior walls 35 of the receptacle.
2. In an oven, refrigerator, or the like, a receptacle, a pair of opposing vertical wire frames, each frame having opposing horizontal shelf-supporting wires connected 40 thereto and projecting into the receptacle, a shelf slideable on the opposing wires and having at its rear portion an outwardly projecting finger adapted to extend below the adjacent shelf-supporting wire, a vertical support for the forward end of the shelf-supporting wires having a stop in the path of the shelf when drawn outwardly with the finger beneath the said wire, hinge-eyes 45 secured to opposing interior walls of the receptacle, and wire hinge-extensions on the frames coöoperating with the hinge-eyes.

3. In an oven, refrigerator, or like receptacle, a shelf-support composed of a wire frame, having vertical side and horizontal top and bottom members, horizontal shelf-supporting wires having their ends attached to the said vertical members and their intermediate portions extending inwardly parallel with the said top and bottom members, means supporting the said inwardly extending portions of the shelf-supporting wires, and shelves slideable on the said wires and having fingers lying normally back of the said intermediate portions of the wires and adapted to ride beneath the said wires when the shelves are drawn forwardly.

4. In an oven, refrigerator, or like receptacle, a shelf-support composed of a wire frame, having vertical side and horizontal top and bottom members, horizontal shelf-supporting wires having their ends attached to the said vertical members and their intermediate portions extending inwardly parallel with the said top and bottom members, means supporting the said inwardly extending portions of the shelf-supporting wires, and shelves slideable on the said wires and having fingers adapted to ride beneath the said wires when the shelves are drawn forwardly.

5. In an oven, refrigerator, or like receptacle, a shelf-support composed of a wire frame, having vertical side and horizontal top and bottom members, horizontal shelf-supporting wires having their ends attached to the said vertical members and their intermediate portions extending inwardly parallel with the said top and bottom members, means supporting the said inwardly extending portions of the shelf-supporting wires, and shelves slideable on the said wires and having fingers adapted to ride beneath the said wires when the shelves are drawn forwardly.

Signed at Pittsburgh, Pa., this 18th day of July, A. D. 1911.

ERNEST RICHARDSON.
